UNITED STATES PATENT OFFICE.

JOHN W. SUTPHIN, OF TRENTON, NEW JERSEY.

SHIFTING-RAIL FOR CARRIAGES.

SPECIFICATION forming part of Letters Patent No. 251,965, dated January 3, 1882.

Application filed November 10, 1881. (No model.)

To all whom it may concern:

Be it known that I, JOHN W. SUTPHIN, a citizen of the United States of America, residing at Trenton, in the county of Mercer and State of New Jersey, have invented certain new and useful Improvements in Shifting-Rails for Carriages; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 is a perspective of one end and a portion of the back of a carriage-seat provided with my improved shifting-rail. Fig. 2 is a detached view of the hand-rail, and Fig. 3 a detached view of the back rail.

20 Like letters refer to like parts in all the figures.

25 My invention relates to those irons usually attached to the seats of carriages for the purpose of providing arm-rests at the ends of the seat and supports for and means to which the back of the seat is secured and the top suitably supported; and it consists in certain improvements in the manufacture of said irons, and in said irons as constructed and combined, 30 as will be hereinafter more fully described, and specifically set forth in the claims.

35 A represents in the drawings the end and a portion of the back of an ordinary carriage-seat, to the upper flanged edges of which are secured the arm-rail B and back rail C. These rails are each cast in malleable iron in a flat condition and with all the necessary projections, studs, supports, and shoulders formed integrally thereon, and either before or after, 40 as desired, the subsequent bending, curving, shaping, or fitting of said rails. The bearing and threaded portions are finished in any desirable manner, and by hand-tools or machinery, as preferred, the shaping and bending being, 45 from the nature of the material from or of which they are made, performed without the use of fire or the necessity of heating the rails, as when forged. The rail B is cast in the condition shown in Fig. 2, and is provided with 50 the attaching-studs a a', the shoulder and stud a', the aperture a², and the extension b and

arm b', which merges into the extension b and is connected to the rail proper by a brace, b². The rail C is cast in the condition shown at Fig. 3, and is provided with an attaching-stud, 55 c, and a top-prop bearing, c', screw-threaded, as shown at c²; butsaid screw-thread is formed afterward, as hereinafter described.

As before stated, each of the irons B and C are cast with all of their elements or subsidiary devices integral therewith and in a flattened condition—that is to say, having all curves in a common plane. After being so cast I finish the attaching-studs by hand-tools, or, what is preferable, by suitable well-known machinery; 60 and it will readily be seen that each rail is of such contour as to facilitate the presentation of each portion thus to be finished to machinery for that purpose, and I then present the aperture a² to screw-threading machinery, and 65 form therein a thread adapted to receive the back rail, C, screw-threaded in like manner at c², as hereinbefore mentioned. All of these operations may be performed in any ordinary bolt and nut threading machine, in a manner well 70 known to mechanicians skilled in their use. I now bend, curve, shape, or fit each rail by curving the extension b of rail B inwardly and against the back board, as shown in Fig. 1, and the shoulder and stud a' is bent outwardly, 75 as shown in said figure. Suitable nuts having been provided, nothing remains but to enter the back rail C into the aperture a² of rail B and secure it there on the screw-threads by 80 turning it therein, and to pass the attaching- 85 studs through apertures in the flanges of the seat and secure them by nuts a³ a³ and c³, as clearly shown in Fig. 1. The same operations upon a duplicate set of rails fit them for attachment to the other end of the seat, (not 90 shown,) completing it and adapting it to support the carriage-top in a manner well known and unnecessary to be described.

Although the particular contour of each of the rails herein shown has advantages, in that the projections are readily reached for manipulation, yet I would not limit myself thereto, but may use other styles or designs of rails with more or less of those advantages connected therewith.

100 The rail C, if desired, may be made of wrought-iron, forged by hand, if desired, and

used in connection with the cast malleable-iron rail B; but I prefer to cast both, as described, and either or both may be forged, as the manner of connecting them to each other and to the seat is not affected by the material of which they are made. Hence they may be of wrought-iron or cast-steel or malleable iron.

Having described my invention and its operation, what I claim as new, and desire to secure by Letters Patent, is—

1. The method of making shifting-rails of carriages herein set forth and described, which consists in casting them in a flattened condition and afterward finishing the attaching and connecting portions thereof, and then bending, shaping, and fitting the same, substantially as shown and described.

2. As an article of manufacture, the cast malleable-iron rail B, provided with the attaching-studs a , shoulder and stud a' , aperture a^2 ,

brace b^2 , and extension b , and arm b' , all of the curvatures therein being in a common plane, substantially as shown and described.

3. In a carriage shifting-rail, the combination of the rail B, provided with the screw-threaded aperture a^2 , and the rail C, provided with the screw-thread c^2 , substantially as shown and described.

4. The combination of the seat A, rail B, and rail C, the latter passing through the former and secured therein by a screw-thread, and both secured to the seat, substantially as shown and described.

In testimony whereof I have affixed my signature in presence of two witnesses.

JOHN W. SUTPHIN.
